UNITED STATES PATENT OFFICE.

PRIMM R. HAWTHORNE, OF BATTLE CREEK, MICHIGAN, ASSIGNOR TO NICHOLS & SHEPARD COMPANY, OF BATTLE CREEK, MICHIGAN.

RADIATOR.

1,090,476.

Specification of Letters Patent. Patented Mar. 17, 1914.

Application filed February 10, 1913. Serial No. 747,340.

To all whom it may concern:

Be it known that I, PRIMM R. HAWTHORNE, a citizen of the United States of America, residing at Battle Creek, in the county of Calhoun and State of Michigan, have invented a certain new and useful Radiator, of which the following is a specification, reference being had therein to the accompanying drawing.

10 This invention relates to radiators designed for use in connection with internal combustion motors, the object in view being to provide a radiator which will be economical to manufacture, and efficient and economical in its operation.

15 A further object of the invention is to provide for a definite and regular path of circulation of the cooling medium throughout the entire radiator structure, causing the 20 cooling medium to travel through the radiator in a thin stream which is constantly in motion, the direction of travel of the stream being largely laterally or crosswise with respect to the direction of the draft or current 25 of air passing between the sections of the radiator.

25 A further object of the invention is to provide a radiator which will eliminate the formation of pockets in various portions of the 30 structure, preventing the accumulation of the cooling medium at any point throughout the system, thus securing a uniform reduction in temperature of the cooling medium.

35 A further object is to arrange the cooling sections in such a way that the soldered seams or joints thereof are accessible at all times, and, therefore, adapted to be repaired, without tearing down the radiator.

40 A further object of the invention is to provide a radiator made up of interchangeable parts or sections, so that it is possible to remove any part or section of the radiator, and to add to or subtract from the number 45 of sections in accordance with the volume of cooling medium to be handled, and the horse-power of the motor in connection with which the radiator is used. It is also possible, in case of accident or leakage of one 50 of the sections, to remove the same, which will lessen the efficiency of the radiator only in proportion to the surface of the section removed.

55 A further object is to produce a more rigid and substantial construction of radiator

which will effectively guard against the injurious effects of internal pressure, and to provide means for firmly clamping together the sections of the radiator with any desired pressure, the latter being limited only by 60 the tensile strength of the tie bolts or studs, hereinafter described.

With the above and other objects in view, the invention consists in the construction, combination and arrangement of parts, as 65 will be hereinafter more fully described, illustrated in the accompanying drawings, and pointed out in the claims hereunto appended.

In the drawings: Figure 1 is a horizontal 70 section through one of the cooling sections of the radiator of this invention, showing the combined braces and baffles in plan view. Fig. 2 is a vertical longitudinal section through a pair of superimposed cooling sections. Fig. 3 is a vertical transverse section 75 through the same. Fig. 4 is an enlarged vertical longitudinal section through a complete radiator, taken in line with the tie bolts or studs of two of the hollow columns. Fig. 5 is a detail vertical section taken 80 diametrically of a portion of one of the columns. Fig. 6 is a detail vertical section, showing the means for draining the radiator.

85 The radiator contemplated in this invention comprises a vertical series of hollow cooling sections 1, 2, 3 and 4, the same being superimposed or arranged one above the other, as shown in Fig. 4, and being spaced 90 at a suitable distance apart to allow a current of air to pass between the sections. Each section comprises a top sheet 5, and a bottom sheet 6, said sheets being of sheet metal of light gage, the top sheet having its 95 marginal edges bent downwardly, as shown at 7, while the marginal edges of the lower sheet 6 are bent around the out-turned bottom edges of the top sheet, the seam or joint extending around the entire margin of each 100 cooling section being soldered to prevent leakage.

105 Each cooling section is internally braced, as illustrated in Figs. 1, 2 and 3, by combined bracing and baffle strips 8, each of which is illustrated as of L-shape in cross section, as seen in Fig. 2, said strips 8 extending transversely with relation to the direction of the current of air passing between the cooling sections, as will hereinafter ap-

pear. The strips 8 do not extend the full width of the cooling sections, but terminate in the manner illustrated in the horizontal sectional view Fig. 1, in which it will be observed that every other strip extends from one of the lateral margins of the cooling section across the same to a point beyond the center thereof, while the alternate or remaining strips extend inwardly from the opposite margin of the radiator and terminate short of the opposite side. The strips are thus arranged in staggered relation, so that the cooling medium passing from one end of the cooling section to the other is forced to take a circuitous path and to move back and forth across the radiator and transversely of the direction of movement of the air current passing between the cooling sections.

20 The cooling sections are spaced at a suitable distance apart by means of spacing strips 9, which, it will be observed, extend transversely to the direction in which the strips 8 run. These strips 9 run in a fore and aft direction, or in other words, in lines parallel to the direction of movement of the current of air passing between the cooling sections. Therefore, the cooling medium passing between the strips 8 is carried back and forth in planes transverse to the path traveled by the air current. This results in more thoroughly subjecting the cooling medium to the cooling action of the air current, the cooling medium, such as water, being spread out in a broad thin sheet, during the progressive movement thereof through each cooling section and through the several sections superimposed one above the other.

In addition to the features hereinabove described, each cooling section is provided with openings 10 and 11 in alignment with each other in the top and bottom sheets, as shown in Figs. 1 to 4, inclusive, the said openings being adapted to receive the heads or sections of the columns now to be described.

Referring now to Fig. 4, the cooling sections are shown as connected to a pair of vertically extending hollow columns A and B, each column comprising a cap nozzle 12, and a base nozzle 13. Each column, between the top and bottom nozzles thereof, is provided with a vertical series of heads 14 which are spaced apart by means of spacing rings 15. Two types of these heads are employed in the series of hollow columns. One type has an open center, while the other type has a closed center, or in other words, is provided with a horizontal partition 15' formed with a central hole 16 to receive one of the tie bolts or studs 17, by means of which all parts of the hollow column are tied together and caused to clamp the cooling sections 1, 2, 3 and 4 tightly in place. Each column head or sec-

tion is externally rabbeted at its top and bottom, as shown at 18, leaving a central body portion 19 which is of just sufficient size to fit into one of the openings 10 and 11 of the cooling section, the width of the central portion 20 of each head or section being the same as the distance between the top and bottom sheets 5 and 6 of each cooling section, as clearly shown in Fig. 4. Gaskets 21 in the form of rings of rubber or other suitable material are interposed between the spacing rings 15 and the column heads or sections, as shown in detail in Fig. 5, so as to form tight joints at such points, and each column head or section is provided with lateral openings 22 therein, extending all around the peripheral wall of the section or head, so as to allow for the circulation of the cooling medium between the cooling sections and the column sections. As shown in Fig. 4, the top column section or head, at the left hand side of the figure, is of the closed center type, and the column head or section, at the right hand side, is of the open center type. In the next lower cooling section, the relative arrangement of closed and open heads is reversed. That is to say, the closed head is at the right hand and the open head is at the left hand. This alternate arrangement of open and closed heads is preserved throughout the entire series of cooling sections, the object being to force the cooling medium to follow the direction indicated by the arrows in Fig. 4; that is to say, the cooling medium entering through the inlet 23 of the nozzle A is arrested by the partition 15' of the first column section or head met with, and is forced through the openings 22 lengthwise of the top cooling section 1. The cooling medium then passes in through the lateral openings 22 of the column head or section at the opposite end of the cooling section, and thence downwardly into the column section or head below, which is of the closed type, and, therefore, forces the water to pass in a reverse direction through the next lower cooling section. This relative arrangement of parts is carried out throughout the entire series of sections, so that the water passes back and forth through all of the sections, until it finally issues through the outlet 24 of the base nozzle 13. Under the preferred embodiment of the invention, each tie bolt or stud 17 is threaded at its lower end, as at 25, and screwed into a threaded opening in the base nozzle, while the upper end thereof is threaded to receive a clamping nut 26. The cap nozzle A is also formed with a stuffing box 27, in which is placed packing 28, and a gland 29 for compressing the packing around the tie bolt or stud 17, the gland being pressed inwardly by means of the nut 26 simultaneously with the operation of clamping all of the sections of the 130

radiator together. In order to provide for drainage of the radiator and prevent the freezing of the same, the central opening 16 in each column head or section of the closed 5 type is slightly larger than the external diameter of the tie bolt or stud 17, as shown in Fig. 6. Therefore, when the cooling medium, such as water, is at rest and the bottom connection of the radiator left open, the 10 water will find its way downwardly through the hollow columns into the base nozzles 18 and outwardly through the openings 24, into one of which a threaded plug or stop 30 may be screwed, as shown at the right 15 hand end of Fig. 4. As to the arrangement of the open and closed column heads or sections, it will be observed that all of the cooling sections are identical, but in assembling the 20 cooling sections, they are alternately turned end for end, as shown in Fig. 4, which has the effect of bringing the closed and open sections of the column into the desired arrangement to effect the definite path of circulation of the cooling medium, as 25 hereinabove described. If desired, a forced circulation of the cooling medium may be obtained by the use of a suitable force pump (not shown). Such pump is not absolutely necessary, however, as it is possible to use 30 the ordinary thermo-siphon system of circulation with the radiator hereinabove described.

From the foregoing description, it will now be seen that a forced definite and regular path of circulation is provided for the cooling medium, and that it is carried in a thin stream through the cooling sections, the direction of travel being back and forth, both transversely and longitudinally of the 40 cooling sections, the cooling medium, during a portion of its travel, being directed back and forth and transversely with respect to the direction of movement of the draft or current of air passing between the cooling, 45 sections, thereby more quickly and efficiently lowering the temperature of the cooling medium. As the entire body of the cooling medium is kept moving, the formation of pockets is reduced to a minimum, and the 50 uniform reduction of temperature obtained throughout the entire body of the cooling medium. As all of the cooling sections are identical, one or more of said sections may be removed and replaced, thus enabling the 55 radiator to be quickly repaired, in case of damage or injury thereto. Repairs may also be easily made without taking down the radiator, in view of the fact that the soldered 60 joints of the cooling sections are all at the outer marginal edge thereof, where they are readily accessible.

The radiator hereinabove described allows for an unusually large amount of cooling surface presented to the draft of air, and it 65 is possible to use a less amount of cooling

medium on account of the definite path of movement of the thin stream passing through the sections of the radiator.

The construction, hereinabove particularly described and illustrated in the drawings, 70 also results in a more rigid and substantial construction of radiator, as the sheets of which the cooling sections are composed are thoroughly braced both against internal and external pressure.

What is claimed is:

1. A radiator for internal combustion motors, comprising a vertical series of horizontal hollow cooling sections superimposed in substantially parallel relation, each cooling section composed of top and bottom sheets which are spaced apart and joined together at their marginal edges, bracing strips all parallel to each other, interposed between and crossing the space between said top and bottom sheets, extending transversely of the path of the air between the sections and arranged in staggered relation forming baffles which cause the cooling medium to take a corresponding direction, and spacing members, located exteriorly of and interposed between the cooling sections, said spacing members all being parallel to each other, crossing the space between adjacent sections and extending parallel to the path of movement of the air, and perpendicularly to said bracing strips. 80

2. A radiator for internal combustion motors, comprising a vertical series of horizontal hollow cooling sections superimposed in substantially parallel relation, hollow columns arranged in spaced relation to each other piercing the cooling sections and each embodying a vertical series of superimposed heads, each of which is formed with lateral openings communicating with one of the cooling sections, certain of said heads being centrally open and the others closed, the closed heads alternating with the open heads and being arranged in such relation to each other and the cooling sections as to impart a definite path of circulation to the entire body of the cooling medium, all of the heads being rabbeted to receive the top and bottom sheets of the cooling sections, spacing rings 100 interposed between the heads, and tie bolts passing vertically through said columns and serving to clamp all of the heads and cooling sections together, the closed heads being formed with central bolt holes sufficiently 105 larger than the bolts to permit drainage. 110

3. A radiator for internal combustion motors, comprising a vertical series of horizontal hollow cooling sections superimposed in substantially parallel relation, hollow columns arranged in spaced relation to each other piercing the cooling sections and each embodying a vertical series of superimposed heads, each of which is formed with lateral 120 openings communicating with one of the 125 cooling sections, and tie bolts passing vertically through said columns and serving to clamp all of the heads and cooling sections together, the closed heads being formed with central bolt holes sufficiently 130 larger than the bolts to permit drainage.

cooling sections, certain of said heads being centrally open and the others closed, the closed heads alternating with the open heads and being arranged in such relation to each other and the cooling sections as to impart a definite path of circulation to the entire body of the cooling medium, and tie bolts passing vertically through said columns and serving to clamp all of the heads and cooling

sections together, the closed heads being 10 formed with central bolt holes sufficiently larger than the bolts to permit drainage.

In testimony whereof I affix my signature in presence of two witnesses.

PRIMM R. HAWTHORNE.
